CUSHIONING UNIT

Emil H. Blattner, Rochester, N. Y., assignor to
 The Symington-Gould Corporation, Rochester,
 N. Y., a corporation of Maryland

Application July 27, 1938, Serial No. 221,612

24 Claims. (Cl. 267—9)

The present invention relates to a spring or cushioning unit or device adapted to be used in combination with resilient means of a different character for supporting a superimposed load or bolster member of a railway truck.

An object of the instant invention is the provision, in a spring or cushioning unit, of an association of instrumentalities whereby a central or axially disposed resilient element is initially compressed, and when the unit is placed in service the resilient element is further energized, to thereby prevent a near permanent set taking place in the element while the unit is retained in stock or reserve supply prior to its being placed in service.

Another object of the invention is to resiliently and frictionally resist the compressive movement of a cushioning device which has means associated therewith to decrease the frictional forces during an expansive movement of the device.

A further object of the invention is to energize an axially disposed resilient element of a cushioning unit in such a manner as to gradually increase the radial forces exerted by said resilient element and consequentially increase the frictional forces resisting the compressive movement of the unit.

From an inspection of the accompanying drawings which form a part of the present specification the above-recited as well as numerous other objects will become apparent.

By now considering the several figures of the drawings which disclose exemplary forms of the invention, it will be found that:

Figure 1 is a vertical sectional view of a cushioning device embodying a type of the present invention and illustrating the associated parts in a relation they attain when the device is free from a superimposed load.

Figure 2 is a vertical sectional view of the device disclosed by Figure 1 but showing the component parts thereof in a relation they may assume when a superimposed load is applied to the device.

Figure 3 is a horizontal sectional view taken along the lines 3—3 of Figure 1 and looking in the direction of the arrows.

Figure 4 is a horizontal sectional view taken along the lines 4—4 of Figure 1 and looking in the direction of the arrows.

Figure 5 is a vertical sectional view of a cushioning unit embodying another type of the present invention and showing the parts thereof in their respective relation when the unit is relieved of a superimposed load.

Figure 6 is a vertical sectional view of the unit disclosed by Figure 5 and illustrating the parts of the unit in the respective relation they may assume when a load is applied to the unit.

Figure 7 is a horizontal sectional view taken along the lines 7—7 of Figure 5, looking in the direction of the arrows.

By now referring to the drawings in detail, wherein like reference characters indicate like parts, and initially considering the structure disclosed by Figures 1 to 4, inclusive, the cushioning unit or device is generally designated by the numeral 1. Constituting a portion of the unit is a tubular or barrel member 2 comprising a sleeve 3 having a radial flange 4 extending therefrom adjacent one end thereof. The casing or sleeve is desirably formed with an axial bore 5 which is preferably machined to present a smooth or even inner cylindrical surface 6. The bore extends entirely through the sleeve in order to facilitate the process of machining. Positioned in the bore 5 adjacent the flanged end of the sleeve is a closing piece or end plate 7 which is applied to the sleeve under pressure so as to prevent it from being displaced. The closing piece is formed with an inwardly convoluted portion 8 to present an outwardly facing relief 9 which forms a receptacle for a lug (not shown) provided on a superimposed member for retaining the associated extremity of the unit in a predetermined position. It will, of course, be clearly understood that the closing piece may, if desired, be formed integrally with the sleeve.

Intimately associated with the sleeve is a plurality of counterpart segmental friction shoes 10 each of which includes a vertically disposed stem portion 11 and a radially extending flange or lug 12 positioned adjacent one or the lower extremity of the stem portion and directed outwardly of the device. The shoe stems are arranged to partially extend into the sleeve bore so as to be capable of movement in either direction and are desirably formed as a ring sector in horizontal section, as most clearly illustrated in Figure 3, to form, in assembled relation, a cylindrical housing provided with an outer surface 13 thereof in bearing relation and coaxially formed with the sleeve surface 6. Positioned adjacent the flanged end of the shoes is an annular or ring member 14 having an undercut or relief 15 on its underside to accommodate the shoe flanges. It will be noted that the annular member and shoes are interlocked so as to allow the former to act as a medium by which the shoes are urged longitudinally of the device with respect to the

tubular member during the expansive movement of the device.

Forming a resilient means which assists in resisting the compressive movement of the unit, as well as forming the primary means by which the unit is expanded or returned to normal position, is a helical or coil spring 16 extending circumjacent the sleeve 3 in spaced relation thereto and reacting against the tubular member flange 4 and annular member 14. The term "normal" is herein used to denote a unit or device having the component parts thereof in the respective relation they assume when the unit is subjected to the normal pressure of a superimposed load or bolster such as disclosed by Figure 2 of the drawings.

Positioned within the shoe stem formed housing and disposed axially of the unit is a cylindrical member 17 which is formed of rubber or any other inherently resilient material which may be employed to perform the function intended. The cylinder 17, before application to a unit, is desirably formed of a circumferential dimension greater than the corresponding dimension of the cylinder engaging portion of the assembled shoe stems, and in this manner the cylinder is pre-formed so that, upon application to the unit, it is initially compressed between the shoe stems and thereby capable of resiliently urging the shoe stems radially of the unit and into intimate contact with the sleeve or casing 3. By reason of this recited arrangement, the movement of the shoe stem surfaces 13 over the casing surface 6 will create frictional forces, retarding both the compressive and expansive movement of the unit or device. It will be noted that, when removed from a unit, the cylinder is formed with plane end surfaces substantially perpendicular to the longitudinal axis thereof and, upon assembly with the associated elements of the unit, the rubber or resilient mass flows outwardly of the ends to present upper and lower spherically convex end surfaces 18 and 18^a respectively. It will, of course, be understood that the end surfaces of the cylinder may be so pre-formed to present end surfaces of any desirable configuration, and it is not the present intention to limit the cylinder end surfaces to a spherical and convex disposition.

It has been found that rubber or similar material, when subjected to constant compressive, tensional or shear forces, normally has a tendency to assume a near-permanent set whereby the rubber mass loses a portion of its inherent resilient value for accomplishing the purpose intended. Cushioning units of the present type are at times assembled by the manufacturer and shipped to the consumer, the latter of whom oftentimes retains the units in stock or reserve supply for a period of time before placing them in service. If the resilient cylinder were subjected to the service forces for a considerable length of time while the unit remained in stock, it will be understood from the above that the unit will not usually be as effective and capable of absorbing the service loads for which it was originally designed.

With this thought, therefore, in mind, there is provided adjacent the shoe flanged end of the device a plunger or cylinder actuator 19 which is adapted to move longitudinally or axially of the device into the shoe stem formed housing. The plunger preferably comprises a cylindrical or circular portion 20 formed coaxial with the shoe stems and tubular member sleeve and is

positioned in spaced relation to and inwardly of the shoe stems. The plunger circular portion forms a receptacle for an associated positioning means (not shown) for retaining the lower extremity of the unit in a predetermined position and preventing the accidental displacement thereof. The plunger circular portion is closed at one end thereof by means of a convex portion 21 which has an inwardly facing spherical convex surface 22 slightly contacting the lower spherical end surface 18^a of the cylinder 17 when the unit is not in service, as most clearly illustrated in Figure 1. So as to limit the movement of the plunger outwardly of the device there is provided radially disposed lugs or fingers 23 extending outwardly of the plunger circular portion and into apertures 24 in the shoe stem. The apertures 24 are positioned intermediate the ends of the shoe stems and are formed as recesses along the transverse edges of the stems. The apertures or recesses are elongated so as to allow a free unrestricted movement of the plunger with respect to the shoes inwardly of the device. The plunger circular portion is arranged and constructed so as to have a portion thereof extend outwardly of the device beyond the flanged end of the friction shoes when the unit is not in service so that, upon application of a superimposed load to the unit during service, the plunger will be urged inwardly of the device to actuate or energize the cylinder 17 and thereby materially increase the component radial pressure acting on the shoe stems and consequently the frictional forces which act upon the stem surfaces 13 and sleeve surface 6 when the shoes and tubular member are moved with respect to one another.

The intimate convex surfaces 18^a and 22 provide for gradually increasing the radial pressure exerted by the cylinder 17, and by the same token when the plunger moves outwardly of the device the radial pressure will be gradually decreased. If, however, during service, the frictional forces are greater than the expansive capacity of the helical spring to such a degree that the helical spring is incapable of moving the friction shoes away from the tubular member, the energized cylinder will urge the plunger outwardly of the device, thereby decreasing the frictional forces by an amount sufficient to allow the helical spring to completely expand the unit. The circular portion of the plunger has the outermost end thereof flared, as at 25, to increase the outer or spring plate bearing area of the plunger.

Positioned in the close proximity of the end surfaces 18 of the cylinder is a beading, stationary means or bearing shoulder 26 extending inwardly of each shoe stem from adjacent the end thereof opposite from the flanged end. The purpose of the shoulders 26 is to reinforce the shoe stems as well as present an abutment for the periphery of the cylinder end 18. When the unit is subjected to service loads the plunger moves inwardly of the device, displacing the resilient mass vertically of the unit, and by reason of the bearing shoulders 26 only partially restricting the passage of the resilient mass, the cylinder will be placed in shear.

The closing piece convoluted portion 8 has an inwardly facing spherical convex surface 27 normally in spaced relation to the convex end surface 18^a of the cylinder 17. The surfaces 27 and 18^a are arranged and disposed so that, after a predetermined compressive movement of the unit,

the surfaces will engage and the plunger will gradually compress the resilient cylinder, to thereby further increase the component radial forces acting against the shoe stems 11. It will be noted that the compressed cylinder will, upon the initial expansive movement of the unit and by reason of its acting against the closing piece, assist the soil spring in urging the tubular member and shoes apart.

By now referring to the modification of the present invention illustrated by Figures 5 to 7, inclusive, the cushioning unit or device disclosed is indicated by the numeral 1. The unit includes a tubular or barrel member 2^a having a sleeve or casing 3^a terminating in a top or radially disposed flange or shelf 4^a. The sleeve 3^a is provided with an axially disposed bore 5^a which is preferably machined and extends entirely through the casing. The bore 5^a is closed adjacent the flanged end of the casing by means of a closing piece or end plate 7^a which is applied to the casing under pressure, the relative diameters of the closing piece and bore being of a dimension to require such an application. In this manner the end plate completely prevents the entrance of foreign substance to within the sleeve as well as prevents an accidental separation between the closing piece and sleeve. The closing piece is provided with an outwardly facing recess 9^a which may accommodate a positioning means on an associated structure to retain the upper extremity of the unit in a predetermined position.

Arranged to move relatively to the tubular member and axially of the device is a plurality of substantially counterpart segmental friction shoes 10^a each of which includes a stem portion 11^a partially extending into the sleeve or casing and formed as a ring sector in horizontal cross section. The shoe stems are provided with outer cylindrical surfaces 13^a in bearing relation and coaxial with an inner cylinder surface 6^a of the sleeve 3^a, to thereby provide an appreciable amount of bearing area between the shoe stems and sleeves. The shoes are provided with radial flanges or legs 12^a extending outwardly of the stems from adjacent one or the lower extremity thereof. Superimposed upon the shoe flanges is an annular or ring member 14^a which has an undercut or relief portion 15^a formed on its outer side to accommodate or form a pocket for the shoe flanges. Interposed between and acting against the tubular member shelf 4^a and annular member 14^a is a coil or helical spring 16^a arranged circumjacent the sleeve 3^a in spaced relation thereto. When the unit has been compressed and subsequently relieved of a superimposed load the helical spring will urge the tubular member and shoes apart to expand the unit and return it to its normal position.

Positioned between the shoe stems is a cylindrical mass of resilient material 17^a preferably formed of rubber or similar inherently resilient substance which may be employed to perform the function intended. The cylinder 17^a, like the cylinder of the previously described structure, is desirably formed in its free state with a circumferential dimension greater than the circumferential dimension of the cylinder confining portion of the assembled shoe stems. In this manner the cylinder, when applied to a unit, is under an initial compression and capable of urging the shoe stems radially of the device and the stem surfaces 13^a into intimate contact with the sleeve surface 6^a. The cylinder is de-

sirably pre-formed with end surfaces disposed in a plane substantially perpendicular to its longitudinal axis so that, upon compression the cylinder for application to the unit, the resilient mass will flow outwardly of the unconfined ends thereof to present upper and lower spherical convex surfaces 18^b and 18^c, respectively.

Like the previously described structure, the present embodiment has the component parts thereof arranged so that the cylinder is relieved of its service load while being retained in reserve supply or stock. In this manner the cylinder is under very little compression while the unit is not in service, and any tendency of the cylindrical mass to set will be delayed. To accomplish the above, a plunger 19^a is positioned intermediate the shoe stems adjacent one or the flanged end thereof and is arranged to move axially of the device to energize the resilient cylinder. The plunger desirably comprises a circular or cylindrical portion 20^a of a diameter less than the inner diameter of the assembled shoes so as to be capable of an unrestricted movement longitudinally of the device. The plunger circular portion is desirably closed at its inner extremity by means of an arcuate plate portion 21^a which is provided with an inwardly facing spherical surface 22^a the latter of which merely contacts the lower cylinder end 18^c when the unit is not in service. Lugs or fingers 23^a extend radially of the plunger circular portion and project into suitable apertures 24^a in the shoe stems positioned adjacent the flanged end thereof to form guiding means during the axial movement of the plunger as well as retain the plunger in assembled relation with the associated structure of the unit. The apertures 24^a are positioned along the lateral or transverse edges of the shoe stems and are desirably elongated in order to allow movement of the plunger inwardly of the device while limiting movement of the plunger in the opposite direction. The plunger circular portion is desirably flared, as at 25^a, to thereby increase the outer bearing area of the plunger.

When a unit of the present structure is not in service the plunger circular portion has a portion thereof extending beyond the flanged end of the friction shoes and annular member, as most clearly illustrated in Figure 5, and while the plunger is thus positioned the resilient cylinder is relieved of service loads and merely under initial compression. However, when the unit is placed in service and a superimposed load is applied thereto the plunger will be urged or moved axially of the device to energize the cylinder and substantially increase the component radial pressure exerted against the shoe stems. This latter pressure will increase the frictional forces acting upon the stem surfaces 13^a and sleeve surface 6^a when the shoes are moved relatively to the sleeve during an expansive or compressive movement of the device. It will be noted that by reason of the intimately related convex surfaces 18^c and 22^a the frictional forces of a completely compressed unit will be gradually decreased in order to allow relative movement between the shoes and tubular member in a direction away from one another during the expansive movement of the device if the frictional forces are sufficiently great to prevent the helical spring from returning the unit to expanded position.

The shoe stems are provided with inwardly directed flanges 28 which are positioned adjacent

the other or top extremity thereof and are triangular in form when viewed from the top, as most clearly illustrated in Figure 7. Reacting against the vertical displacement of the resilient mass forming the cylinder, during the compressive movement of the unit, is a substantially stationary member or bearing pad 28^a which is interposed between the shoe flanges 28 and the upper surface 18^b of the cylinder. The bearing pad is provided on one side thereof with a conically formed surface 29 which bears directly against a correspondingly formed surface 30 on the shoe flanges 28. This particular disposition of surfaces 29 and 30 maintains the bearing pad in a predetermined position and prevents shifting thereof laterally of the device. The bearing pad 28^a has an inwardly facing spherical convex surface 31 in intimate contact with the upper convex surface 18^b of the cylinder so that, during a compressive movement of the device, the cylinder will be gradually compressed to correspondingly increase the component radial pressure exerted against the shoe stems, and by the same token the component radial pressure may be gradually decreased during the expansive movement of the device. It will be observed that the component parts of the structure under immediate consideration are constructed and arranged to place the cylinder under compression, while the parts of the previously described structure are so arranged that the cylinder is initially under compression, and when the unit is placed in service the resilient mass is displaced in a manner to develop shear stresses in the cylinder in addition to the compressive forces.

It will, of course, be clearly understood that it is not the present intention to limit the invention to the illustrated and described structures but that various alterations and changes may be made thereto without departing from within the spirit and scope of the appended claims.

I claim:

1. In a cushioning unit, in combination, a tubular member, segmental shoes movable relative to said tubular member, an annular member in bearing relation with said shoes, spring means positioned so as to react against said tubular and annular members for urging them apart, resilient means arranged to urge said shoes into engagement with said tubular member, a plunger positioned adjacent the extremity of said shoes and having a surface thereof in bearing relation with said resilient means, said plunger having a portion thereof extending beyond said shoes and being movable relative to said shoes whereby, upon a compressive movement of said unit, said plunger will move inwardly of said unit entirely within the confines of said shoes to energize said resilient means.

2. In a cushioning unit, in combination, a barrel member, segmental shoes movable relative to said barrel member, an annular member extending circumjacent and in bearing relation with said shoes, spring means adapted to react against said barrel and annular members for urging said barrel member and shoes apart, rubber means interposed between said shoes for urging them radially into bearing relation with said barrel member, a plunger movably associated with said shoes adjacent one end thereof and in bearing relation with said rubber means whereby, upon an initial compressive movement of said unit, said plunger will move relative to said shoes and energize said rubber means, and means associated with said barrel member adapted to en-

gage said rubber means to additionally energize said rubber means after a predetermined compressive movement of said cushioning unit.

3. In a resilient device, in combination, a tubular member, a plurality of segmental shoes partially extending within and movable relative to said tubular member, spring means circumjacent said tubular member and adapted to urge said tubular member and shoes apart, resilient means interposed between said shoes for urging them radially of the device into bearing engagement with said tubular member, movable means having outstanding lugs projecting through apertures in said shoes to limit the travel of the movable means outwardly of said device, said movable means bearing against said resilient means so that, upon a compressive movement of said device, said movable means will be urged entirely within the confines of said shoes and energize said resilient means to increase the radial pressure of said shoes against said tubular member.

4. A cushioning unit, in combination, a tubular member, segmental shoes having stem portions thereof extending into said tubular member, flanges extending radially of said shoe stems in spaced relation to said tubular member, annular means extending circumjacent said shoe stems and bearing against said shoe flanges, spring means interposed between said tubular and annular members, rubber means interposed between said shoe stems and urging them radially into bearing relation with said tubular member, a plunger interposed between said shoes having a surface thereof in bearing relation with said rubber means, said plunger having lugs outstanding therefrom and extending into apertures in said shoe stems to limit the travel of said movable means outwardly of said unit, said plunger, upon a compressive movement of said unit, being adapted to move entirely within the confines of said shoes to energize said rubber means.

5. In a resilient device, in combination, a tubular member, a plurality of segmental shoes partially extending within and movable relative to said tubular member, spring means circumjacent said tubular member in spaced relation thereto and adapted to urge said tubular member and shoes apart, bearing means associated with said shoes adjacent one end thereof, resilient means interposed between said shoes for urging them radially of the device into bearing relation with said tubular member, said resilient means having an end portion in intimate contact with said bearing means, movable means associated with said shoes adjacent the other end thereof and having outstanding lugs projecting through apertures in said shoes, said movable means bearing against said resilient means whereby, upon a compressive movement of said device, said movable means will urge said resilient means against said bearing means to subject said resilient means to shear stresses.

6. In a cushioning unit, in combination, a tubular member, segmental shoes having stem portions thereof extending into said tubular member, flanges extending radially of said shoe stems, annular means bearing against said shoe flanges, spring means interposed between said tubular member and annular means, resilient means interposed between said shoe stems and urging them radially into bearing relation with said tubular member, a plunger interposed between said shoes having a convex surface thereon in bearing relation with a convex surface on

said resilient means, said plunger having lugs outstanding therefrom and extending into slots in said shoe stems, said plunger, upon a compressive movement of said unit, being adapted to move entirely within the confines of said shoes to gradually energize said resilient means.

7. In a resilient device, in combination, a tubular member, a plurality of segmental shoes partially extending within and movable relative to said tubular member, spring means circumjacent said tubular member and adapted to urge said tubular member and shoes apart, stationary means associated with said shoes adjacent one end thereof, resilient means interposed between said shoes for urging them radially of the device into bearing engagement with said tubular member, said resilient means bearing against said stationary means, movable means associated with said shoes adjacent the other end thereof and having outstanding lugs projecting through slots in said shoes, said movable means bearing against said resilient means so that, upon a compressive movement of said device, said movable means will urge said resilient means against said stationary means, and means associated with said tubular member adapted to contact said resilient means to further energize the latter after a predetermined compressive movement of said device.

8. In a cushioning unit, in combination, a tubular member having an axial bore extending therethrough, a closing piece positioned in said bore adjacent one end thereof, segmental shoes having portions thereof extending into said bore, spring means arranged to urge said tubular member and shoes apart, means extending inwardly of said unit from adjacent one end of said shoes, a resilient cylinder positioned axially of said unit for urging said shoes radially of the unit and into bearing relation with said tubular member, a plunger positioned between and movable relative to said shoes adjacent the other end thereof whereby, upon a compressive movement of said unit, said plunger will urge said cylinder longitudinally of the device and said cylinder will react against said shoe means.

9. In a cushioning unit, in combination, a tubular member having an axial bore extending therethrough, a closing piece positioned in said bore adjacent one end thereof, said piece having a convex surface facing inwardly of the bore, segmental shoes having portions thereof extending into said bore, spring means arranged to urge said tubular member and shoes apart, means extending inwardly of said unit from adjacent one end of said shoes, a resilient cylinder interposed between said shoes for urging them radially of the unit and into bearing relation with said tubular member, a plunger positioned between and movable relative to said shoes adjacent the other end thereof whereby, upon an initial compressive movement of said unit, said plunger will urge said cylinder against said shoe means and, after a predetermined compressive movement of the unit, said convex surface will engage and gradually energize said cylinder.

10. In a cushioning unit, in combination, a tubular member having a machined bore extending therethrough, a removable closing piece occupying said bore adjacent one end thereof, segmental shoes movable relative to said tubular member, an annular member in bearing relation with said shoes, spring means arranged between said tubular and annular members for urging said tubular member and shoes apart, trans-

versely acting resilient means urging said shoes into engagement with said tubular member, a plunger positioned adjacent an extremity of said shoes and having a convex surface in bearing relation with said resilient means, said plunger being movable relative to said shoes whereby, upon a compressive movement of said unit, said plunger will move inwardly of said unit and gradually energize said resilient means.

10. In a cushioning unit, in combination, a tubular member, shoes having portions thereof extending within said tubular member, spring means acting between said tubular member and shoes for urging them apart, a compressible cylindrical member interposed between said shoe portions for urging them radially and into engagement with said tubular member, a plunger having outstanding means extending through apertures in said shoes adjacent one end thereof so as to normally restrict the movement of the plunger outwardly of the unit while permitting movement of the plunger inwardly of the unit, and means associated with said tubular member adapted to additionally energize said compressible cylindrical member after a predetermined compressive movement of said cushioning unit.

12. In a cushioning device, in combination, a tubular member, shoes movable longitudinally of the device and extending into said tubular member, spring means acting between said tubular member and shoes, a compressible cylinder positioned between said shoes for urging them into engagement with said tubular member, a plunger positioned adjacent one end of said shoes having a portion thereof extending outwardly of said shoes, said plunger being adapted to develop shear stresses in said cylinder when a load is applied to said device.

13. In a cushioning device, in combination, a tubular member, shoes movable longitudinally of the device and extending into said tubular member, spring means acting between said tubular member and shoes, a compressed rubber cylinder positioned between said shoes for urging them radially into engagement with said tubular member, a plunger positioned adjacent one end of said shoes and having a portion thereof extending outwardly of said shoes, and said plunger engaging said cylinder and being adapted to move inwardly of the device entirely within the confines of said shoes during a compressive movement thereof to thereby increase the radial pressure exerted on said shoes.

14. In a cushioning device, in combination, a tubular member, shoes movable longitudinally of the device and extending into said tubular member, spring means acting between said tubular member and shoes for urging them apart, a compressed rubber cylinder positioned between said shoes and urging them into engagement with the tubular member, bearing shoulders on said shoes adjacent one end of said cylinder, a movable plunger adjacent the other end of said shoes having a portion thereof extending beyond the corresponding end of said shoes so that, when said unit is initially compressed, said plunger will urge said cylinder into engagement with said shoulders and thereby subject said cylinder to shear stresses.

15. In a cushioning device, in combination, a tubular member, shoes movable longitudinally of the device and extending into said tubular member, spring means acting between said tubular member and shoes for urging them apart, a compressed rubber cylinder positioned be-

tween said shoes and urging them into engagement with said tubular member, flanges on said shoes adjacent one end thereof, a bearing pad between said flanges and cylinder, a movable plunger adjacent the other end of said shoes having a portion thereof extending beyond the corresponding end of said shoes so that, when said unit is initially compressed, said plunger will urge said cylinder into engagement with said bearing pad and thereby increase the compressive forces in said cylinder.

16. A tubular member for a cushioning unit comprising a sleeve having a machined bore extending completely therethrough, a radial flange adjacent one end of said sleeve forming a ledge for an associated spring, and a closing piece applied to said sleeve under pressure and positioned adjacent the flanged end of said sleeve.

17. A tubular member for a cushioning unit comprising a sleeve portion having a machined bore extending therethrough, a radial flange adjacent one end of said sleeve to form a ledge for an associated spring, and a closing piece applied to said sleeve under pressure and positioned adjacent the flanged end of said sleeve, said closing piece having a spherical convex surface adapted to engage and gradually energize an associated resilient element.

18. In a cushioning device, in combination, a tubular member, segmental shoes positioned within and movable relatively to said tubular member, spring means adapted to urge said tubular member and shoes apart, a compressed resilient cylinder interposed between said shoes and urging them radially of the device into intimate contact with said tubular member, and movable means associated with an extremity of said shoes and having a portion thereof extending beyond said shoes outwardly of the device, said movable member, upon an initial compressive movement of said device, being urged within the confines of said shoes to additionally energize said resilient cylinder.

19. In a cushioning device, in combination, a tubular member, segmental shoes positioned within and movable relatively to said tubular member, a compressed resilient cylinder interposed between said shoes and urging them radially of the device into intimate contact with said tubular member, said resilient cylinder having a downwardly facing convex surface, and movable means associated with an extremity of said shoes and having a convex surface in engagement with said cylinder convex surface, said movable means being adapted to travel inwardly of said device during a compressive movement thereof to gradually energize said resilient cylinder.

20. In a cushioning device, in combination, a tubular member, shoes movable longitudinally of the device and extending into said tubular member, spring means acting between said tubular member and shoes for urging them apart, a

compressed rubber cylinder positioned between said shoes and urging them into engagement with said tubular member, flanges on said shoes adjacent one end thereof, a bearing pad engaging said flanges and having a convex surface in intimate contact with said rubber cylinder, a movable plunger adjacent the other end of said shoes having a portion thereof extending beyond the corresponding end of said shoes so that, when said unit is initially compressed, said plunger will urge said cylinder against said convex surface and thereby gradually energize said cylinder.

21. In a cushioning device, in combination, a tubular member, shoes movable longitudinally of the device and extending into said tubular member, a compressed rubber cylinder having oppositely disposed arcuate surfaces and being positioned between said shoes urging them outwardly of the device into engagement with said tubular member, flanges on said shoes adjacent one end thereof, a bearing pad underlying said flanges and having a convex surface in intimate contact with one of said rubber cylinder convex surfaces, and a plunger adjacent the other end of said shoes having a convex surface in intimate contact with the other of said rubber cylinder convex surfaces, said plunger being adapted to move inwardly of the device to gradually energize said rubber cylinder.

22. In a cushioning device, in combination, a tubular member, shoes movable longitudinally of the device and extending into said tubular member, a compressible cylinder positioned between said shoes for urging them into engagement with said tubular member, a plunger positioned adjacent one end of said shoes being adapted to develop shear stresses in said cylinder upon a compressive movement of said device, and means on said tubular member adapted to engage and energize said cylinder after a predetermined compressive movement of said device.

23. In a cushioning device, in combination, a tubular member, shoes movable relative to and extending into said tubular member, a compressible means positioned between said shoes for urging them into engagement with said tubular member, and a movable member positioned adjacent one end of said device and being adapted to develop shear stresses in said compressible means upon an initial compressive movement of said device.

24. In a cushioning device, in combination, a barrel member, shoes movable longitudinally and transversely of said device and extending into said barrel member, a rubber means positioned between said shoes for urging them into engagement with said barrel member, and a movable member positioned adjacent one end of said device and being adapted to develop shear stresses in said rubber means during the entire compressive movement of said device.

EMIL H. BLATTNER.
